ATTORNEYS.

UNITED STATES PATENT OFFICE.

JOHN W. LAKE, OF ST. LOUIS, MISSOURI, ASSIGNOR TO BOYD-WELSH SHOE COMPANY, OF ST. LOUIS, MISSOURI, A CORPORATION OF MISSOURI.

APPAREL SHOE.

Application filed April 22, 1927. Serial No. 185,755.

This invention relates generally to shoes, heel portion thereof so as to provide said insole with a pair of flap portions arranged 55 one above the other and the shank is passed through a slit in said insole so that the rear portion thereof is interposed between said flap portions while the forward portion of the shank is arranged in contact with the 60 outer face of the insole.

5 10 15 20 25 30 35 40 45 50 55 60 65 70 75 80 85 90 95 100

This invention being to provide an improved arch shank construction for shoes of this type, whereby the tendency of the heels of these shoes to move rearwardly relative to the toe portions of said shoes when the weight of a wearer is supported by the arch portion of the sole of one of said shoes, as when the wearer is stepping off of an elevated article, is eliminated.

Prior to this invention, ladies' shoes of 15 the high heel type have been provided each with an arch shank which comprised a relatively narrow strip of steel or other suitable material and which was of constant width from end to end. Ordinarily, this shank extended from the portion of the sole of the shoe known as the break, but more specifically, the curved point at which the ground-contacting portion of the outsole joins the arch portion of said outsole, to a point a 20 25 30 35 40 45 50 55 60 65 70 75 80 85 90 95 100

very slight distance inwardly beyond the front edge of the heel of the shoe. This construction resulted in a weak spot at the front edge of the heel of the shoe, and consequently it frequently happened that when a greater part of the weight of a wearer of shoes so made was supported by one of said shoes, the excessive weight on the arch portion of the shoe would tend to straighten out the curved arch, with the result that the heel of the shoe would be moved rearwardly relative to the toe portion of the shoe and in this manner the outsole was broken at the forward edge of the heel.

Instead of terminating the arch shank of 40 45 50 55 60 65 70 75 80 85 90 95 100

a shoe made in accordance with this invention at a point adjacent to the front edge of the heel of the shoe as heretofore, the rearmost or heel portion of my improved arch shank extends into and conforms to the shape of the heel portion of the shoe so that this part of the shoe is materially strengthened without rendering the arch portion of the shoe unduly rigid.

Another important feature of my invention 50 55 60 65 70 75 80 85 90 95 100 105

resides in the fact that the insole of a shoe made in accordance with the invention is split longitudinally in a direction forwardly from the edge of the rearmost or

Figure 1 is a perspective of the improved arch shank forming a part of my invention;

Figure 3 is an enlarged section on line 65 70 75 80 85 90 95 100

3—3 of Fig. 2;

Figure 4 is a view of a lady's shoe made in accordance with my invention and shown partly in side elevation and partly in vertical section;

Figure 5 is a cross-section on line 5—5 of Fig. 4.

In Fig. 4 of the drawing, A designates a lady's shoe which is of the type which I 75 will refer to as skeleton shoes, and includes an outsole B, an upper portion C at the toe portion of the shoe, and an upper portion D at the heel portion of said shoe. 1 designates the insole of the shoe A, which insole, 80 as shown clearly in Figs. 2, 3 and 4, is split longitudinally, said split portion being extended forwardly from the edge of the rear or heel portion of the insole to a point forward of the front edge of the heel E of the shoe (Fig. 4). The split heel portion of the insole 1 provides said insole at this point with a lower flap portion 2 and an upper flap portion 3 which are, of course, integrally connected together at their inner 90 ends. While I prefer to provide the insole of my improved shoe construction with flap portions 2 and 3 by splitting said insole longitudinally, it is obvious that one or the other of said flap portions may be made separate and may be secured to the associated flap portion in any suitable manner.

Formed through the lower flap portion 2 of the insole is a slit 4, said slit being extended through said lower flap portion at a slight angle instead of at a right angle to the top and bottom faces of said lower flap portion. This manner of forming the slit 4 provides said slit with a pair of inclined walls 5 which are for a purpose to be hereinafter set forth.

6 designates the arch shank of my improved arrangement which may be formed of steel or fibre or any other material which may be suitable for the purpose. The arch shank 6 is extended through the slit 4 in the lower flap portion 2 of the insole, and the forward portion of said arch shank, that is to say, the portion forward of the slit 4, is interposed between the outsole B and the insole 1 of the shoe. The rear or heel portion of the arch shank 6 is interposed between the flap portions 2 and 3 of the insole, as shown clearly in Fig. 4, and due to the inclined walls 5 of the slit 4, the material 15 at the opposite sides of the slit 4 is not displaced by the arch shank to produce raised portions on the insole. The rear or heel portion of the arch shank 6, which is interposed between the flap portions 2 and 3 of the insole, is shaped to conform to the shape 20 of the heel portion of the shoe, as shown in Fig. 5, and said heel portion of said shank is provided with a plurality of nail-receiving apertures 7 formed therethrough 25 through which nails 10 are driven to secure the heel E of the shoe in place.

In the manufacture of a shoe in accordance with my improved arrangement, the insole and upper are secured together on the last in the usual temporary manner and the arch shank, which is extended through the slit 4 in the insole 1, at this time is secured to the insole by means of a tack 8 at the forward end of the arch shank, and a similar tack 9, which passes through the shank and into the insole at a point adjacent to the front edge of the heel of the shoe, the shank being provided with apertures at these points to receive said tacks. The outsole is then arranged in place on the last on which the shoe is being made, and the outsole, insole and upper are secured together in the usual manner in accordance with which the outsole, insole and upper are sewed together by a row of 45 stitches which extends around the marginal edge of the front portion of the shoe, said row of stitches terminating adjacent to the front edge of the heel E. The outsole, insole and heel portion of the upper are also secured 50 together in the usual manner by tacks which are driven from the outside of the shoe through the outsole, insole and inturned portion of the upper; but these tacks are of such length that they will pass only through the lower flap portion 2 of the insole and will not extend into the upper flap portion 3 thereof.

When the outsole, insole and upper portions of the shoe have been secured together as described, the heel E will be arranged in place 60 on the shoe, and when the upper flap portion 3 of the insole has been moved upwardly to the position in which it is shown in Fig. 2, nails or similar fastening devices 10 will be driven from the inside of the shoe through 65 the apertures 7 in the heel portion of the

shank and through the lower flap portion 2, outsole B, and into the heel E, whereby said heel will be secured in place.

After the fastening devices 10 have been driven into the heel E as described, the upper flap portion 3 of the insole will be moved downwardly to its normal position in contact with the heel portion of the shank and with the upper face of the lower flap portion 2, and said upper flap portion will then be cemented or otherwise secured in this position. It is obvious when the upper flap portion 3 has been secured in its normal position as described that said upper flap portion will effectively cover the heads of the fastening devices 75 10 and will also function as a cushion between the heel portion of the arch shank and the heel of a wearer of the shoe.

Due to the fact that the arch shank of my improved shoe structure extends to the rear 85 end of the shoe instead of terminating adjacent to the front edge of the heel as heretofore, and also because the heel portion of the shank is shaped to conform to the shape of the heel portion of the shoe and is rigidly secured in place by the nails which secure the heel to the shoe, my improved shoe is greatly strengthened at the point where shoes of this type were formerly rather weak, and, therefore, the tendency for the outsole of the 95 shoe to be broken at the front edge of the heel is eliminated. Also, it is pointed out that while the shoe is given additional strength where needed by my improved construction, still the desired flexibility of the shoe at the 100 arch portion thereof is not interfered with.

I claim:

1. An apparel shoe comprising an outsole, an insole, a heel, and an arch shank having a heel portion, said insole being split longitudinally at its heel portion to provide a pair of flap portions one of which is provided with a slit formed therethrough, said arch shank being extended through said slit in a manner to cause the heel portion thereof to be interposed between said flap portions of said insole.

2. An apparel shoe comprising an outsole, an insole, a heel, and an arch shank, said insole being split longitudinally at its heel portion to provide a pair of flap portions one of which is provided with a slit formed therethrough, the heel portion of said arch shank being shaped to conform approximately to the shape of the heel portion of the shoe and said arch shank being extended through said slit in a manner to cause the heel portion thereof to be interposed between said flap portions of said insole.

3. An apparel shoe comprising an outsole, an insole, a heel, an arch shank provided with a heel portion shaped to conform approximately to the shape of the heel portion of the shoe, said insole being split longitudinally at its heel portion to provide a pair of flap por-

tions one of which is provided with a slit formed therethrough, said arch shank being extended through said slit in a manner to cause the heel portion thereof to be interposed between said flap portions of said insole, and fastening devices extended through said heel portion of said arch shank and through a

flap portion of said insole into said heel, said heel portion of said arch shank being covered by a flap portion of said insole. ¹⁰

In testimony whereof, I have hereunto set my hand.

JOHN W. LAKE.
